WILLIAM LIONEL HEAP, OF GRAND HAVEN, MICHIGAN, ASSIGNOR TO WILLIAM HEAP & SONS, OF GRAND HAVEN, MICHIGAN, A FIRM COMPOSED OF WILLIAM HEAP, WILLIAM LIONEL HEAP, AND CECIL R. HEAP.

FLUSHING-VALVE-OPERATING MECHANISM.

1,118,201.

Specification of Letters Patent. Patented Nov. 24, 1914.

Application filed January 10, 1914. Serial No. 811,324.

To all whom it may concern:

Be it known that I, WILLIAM LIONEL HEAP, a citizen of the United States of America, residing at Grand Haven, in the county of Ottawa and State of Michigan, have invented certain new and useful Improvements in Flushing-Valve-Operating Mechanism, of which the following is a specification, reference being had therein to the accompanying drawings.

The invention relates to flushing valve operating mechanisms, being more particularly adapted for use in connection with wooden tanks having metallic linings for holding the water. With such constructions it is usual to mount the operating handle or push button upon the side of the wooden tank, while the valve which is operated by this device is seated upon the bottom of the tank. It has been found with such constructions that after they have been in use for some time the wood of the tank will swell, due to the presence of moisture, and as a consequence the relation between the operating device and the valve actuated thereby is changed. Frequently this change is sufficient to cause the unseating of the valve when the device is in its normal position, which permits the wasting of the water and renders the device inoperative. With the present invention this difficulty has been overcome by providing an operating mechanism which is unaffected by any swelling or contraction of the wooden tank, as hereinafter set forth.

In the drawings: Figure 1 is a perspective view of the flushing tank and valve operating mechanism, with the lining of the tank removed; and Fig. 2 is a cross section showing the tank lining in position. Fig. 3 is a perspective view of the lever fulcrum support.

A is the wooden tank; B is the metallic lining therefor; C is the flushing valve which is normally seated in a fitting D mounted on the bottom of the tank; and E is the operating handle or push button mounted on the wooden tank.

To avoid perforation of the metallic lining and leakage of water therethrough, the connections between the push button E and the valve C are arranged to pass over the upper edge of the tank lining. Thus, where the push button is located near the bottom of the tank, as shown in Fig. 2, there is

necessitated a mounting or fulcrum for the intermediate connections between said push button and the valve, which is located at the upper end of the tank or above the metallic lining. Thus where, as is usual, this fulcrum is mounted upon the upper portion of the wooden tank the swelling of said tank due to moisture will alter the distance between this fulcrum and the point of location of the push button, with a resulting disturbance in the operating mechanism. This I avoid by providing a mounting for the mechanism at the top of the tank which is not attached directly to the side wall of the wooden case, but is secured to the bottom of said case. This mounting is formed of material which is unaffected by moisture, which therefore avoids the difficulty above referred to. Specifically, I preferably employ for this purpose of bar D' of metal which is adapted to lie between the wooden wall of the tank and the metallic lining and which is provided with a foot flange E' secured to the bottom of the tank beneath the lining. The upper end of this bar D' may be attached to the tank wall by a screw F passing through a slot F' in the bar, so as to permit of relative movement due to expansion or contraction of the wood. The upper end of the bar is suitably fashioned for engagement with a fitting G which forms the fulcrum bearing for the lever H or other intermediate connection between the push button and the valve. As shown, this operating connection comprises, in addition to the lever H, a link I depending therefrom and engaging the shank J of a flushing valve, while a second link K extends from the opposite end of the lever downward between the lining of the tank and the wooden case and is connected with the push button E.

With the device constructed as described, the rod D' being mounted upon the bottom of the wooden tank, upon which is also mounted the seat fitting D, there will be no vertical displacement due to the swelling of the wood. Furthermore, as the rod D' is itself unaffected by moisture its upper end will remain in fixed relation to the lower end of the fitting G, and the lever H mounted thereon will be undisturbed. If, however, the wood swells, the screw F will travel along the slot F' and will still support the

rod D' by holding the same adjacent to said wooden wall.

While I have described a specific form of operating mechanism employing a push button and lever connections, it is obvious that my improvement is equally applicable to other types of operating mechanism.

What I claim as my invention is,—

1. The combination with a wooden flushing tank having a metallic lining, of a flushing valve, a seat for said valve mounted on the bottom of said tank, an actuating member for said valve, connecting mechanism between said actuating member and said valve, and a fulcrum for said connecting mechanism at the upper end of said tank, having a moisture-proof support positioned between the wooden wall and the metallic lining and extending from the bottom of the tank.

2. The combination with a wooden flushing tank having a metallic lining, of a flushing valve, a seat for said valve mounted on the bottom of said tank, an actuating device for said valve extending through the wooden tank near the bottom thereof, connecting mechanism between said actuating member and said valve passing over the top of said metallic lining, and a fulcrum for said mechanism at the top of the tank having a moisture-proof support extending to the bottom of the tank between the wooden wall and the metallic lining.

3. The combination with a wooden flushing tank and a metallic lining, of a moisture-proof bar secured to the bottom of the

tank and extending upward between the lining and the wooden side wall, and mechanism for operating the flushing valve mounted on the upper end of said bar.

4. The combination with a wooden flushing tank and a metallic lining, of a moisture-proof bar lying adjacent to the inner face of the wooden side wall of the tank and having a foot at its lower end secured to the bottom of the tank, means for securing the upper end of said bar to the wooden wall, permitting of the relative expansion and contraction of the latter, and operating mechanism for the flushing valve mounted on the upper end of said bar.

5. The combination with a wooden flushing tank and a metallic lining, of a push button valve actuating device mounted on the wall of the tank near the bottom thereof, a flushing valve, a seat therefor mounted on the bottom and within the metallic lining of said tank, connections between said push button and flushing valve extending over the top of said metallic lining, a moisture-proof bar mounted on the bottom of said tank and extending upward between the wooden wall and the metallic lining and a fulcrum for said connecting mechanism mounted on the upper end of said bar.

In testimony whereof I affix my signature in presence of two witnesses.

WILLIAM LIONEL HEAP.
